UNITED STATES PATENT OFFICE.

KARL AUGUST LEHMANN, OF ESSEN, GERMANY, ASSIGNOR TO FRIED. KRUPP AKTIEN-
GESELLSCHAFT, OF ESSEN-ON-THE-RUHR, GERMANY.

TYPEWRITING MACHINE.

Application filed January 14, 1921. Serial No. 437,313.

To all whom it may concern:

Be it known that I, KARL AUGUST LEHMANN, residing at Essen, Germany, a citizen of the German Republic, have invented a 5 certain new and useful Improvement in Typewriting Machines, of which the following is a specification.

My invention relates to typewriting machines having a bar which in its operative 10 position serves to retain the platen in its upper position. In typewriting machines of this particular type, which are known to the art as typewriting machines having automatic case-shift release mechanism, the retaining bar can only be released and the 15 platen returned, after the shifting has been effected and the platen been locked, by depressing a type-key. This, however, embodies a drawback, inasmuch as it may happen that after the platen has been shifted, it may not prove desirable that the particular type, entering into consideration when the platen is in this position shall effect a 20 print. This, however, would be the case in the event of an accidental shifting of the platen. It is the object of my present invention to remedy this defect.

In the annexed drawing two constructional forms of the subject matter of my 25 invention are illustrated by way of example. In this drawing—

Fig. 1 shows a cross section of the first form of execution, with certain parts broken away,

Fig. 2 shows a section on line 2—2 in Fig. 35 1, looking from the left,

Fig. 3 shows a section on line 3—3 in Fig. 1, seen from the top,

Fig. 4 shows a cross section of the second 40 form of execution, with certain parts broken away,

Fig. 5 shows a section on line 5—5 in Fig. 4, looking from the left, and

Fig. 6 shows a section on line 6—6 in Fig. 45 4, seen from the top.

Referring to these drawings, within the frame A of the typewriting machine there is arranged to rock about pivots a¹, a frame-shaped spacing lever B carrying a key b¹ (Fig. 3) and an arm b² communicating with the feed mechanism (not shown) of the machine. A spring C (Figs. 1 and 3) attached to the lever B tends to rotate it in the direction of the arrow x (Fig. 1). On 55 the pivots a¹ there is further mounted a case

shift lever D, carrying two keys d¹ disposed for their part at either side of the key b¹ and acted upon by a powerful spring E which likewise tends to turn this lever in the direction of the arrow x. At the end 60 of the case shift lever D, disposed toward the rear wall of the machine, there is articulated a lifting lever F. This latter is adapted to move by means of a bolt f¹ with in two oppositely disposed slots a³ formed 65 in a stationary part a² of the machine, and carries at its free end a roller f² bearing up from below against a rod g¹ rigidly connected to the bearings (not shown) of the paper-roller G. There is lastly mounted 70 on the pivots a¹, so as to rock, a two-armed frame-shaped lever H. This lever H is provided with two extensions h¹, each of which bears two stops h² and h³ which are all located in the plane of oscillation of the case 75 shift lever D. The stop h² acting under the impulse of a spring J, which engages the levers D and H and which is weaker than the spring E, bears up from below against the case shift lever D. The stop h³ is disposed for a certain measure above the case 80 shift lever D. On the lever H there is linked, to either side of the spacing key b¹, a lever h⁴ having a key h⁵; the said keys h⁵ being located at the particular point of the 85 machine, where in the case of most of the typewriting machines having no automatic case shift release mechanism, the keys of the case shift lever are disposed. Each of the levers h⁴ bears up by means of a projection 90 h⁶ and under the impulse of a spring h⁷ against a stop h⁸ of the lever H. A second stop h⁹ fixed to the lever H and serving to limit a rotation of the lever h⁴ counter to the action of the spring h⁷, lies within the 95 path of the projection h⁶. The axis of rotation of the lever h⁴ is disposed in suchwise that when the key h⁵ is normally depressed, the pressure exerted by the finger will tend to turn the lever h⁴ in the sense in which the 100 spring h⁷ acts. To each of the levers h⁴ there is arranged a bent projection h¹⁰ adapted to engage a stationary stop plate a⁴, as soon as the lever h⁴ comes to bear up with its projection h⁶ against the stop h⁸. 105 At the end of the lever H, disposed toward the rear wall of the machine, there is articulated a U-shaped arm K having two oppositely disposed slots h¹, which a guide bolt f³ fixed to the lifting lever F is adapted 110

to engage. A bar N, adapted to rock about the bolt f^1 , bears up under the impulse of a spring M against the cross piece k^2 of the arm K by means of an extension n^1 . This latter has a projection n^2 extending into the path of the cross piece k^2 . The bar N is moreover provided with another projection n^3 having a bevel surface n^4 , and within the path of which a cross piece a^5 of the stationary part a^2 of the machine is disposed. Finally the bar N is provided with an extension n^5 supporting a roller n^6 . This roller lies within the path of a plate P which, each time a type-key is depressed, is moved in a horizontal direction and is thus enabled to assume the position shown in dash-and-dot lines in Fig. 1.

In the position of the various parts of the machine, as illustrated, and which is the normal position, when the type-keys (not shown) which bear both small and capital letters, are depressed, then small letters come to be written. If now, however, a capital letter is to be written followed by a small letter, then primarily one of the keys d^1 is depressed counter to the action of the spring E; the lever H being at the same time taken along by intervention of the pin h^2 . As a result both the arm K, the lifting lever F along with the bar N and the paper-roller G come to be raised. Simultaneously, the projection n^3 (while the bevel surface n^4 glides along the edge of the cross piece a^5) is forced sideways and engages, at the termination of the motion effected by the case shift lever D, under the action of the spring M the cross piece a^5 . Upon the key d^1 being released, the lifting lever F and therewith also the paper-roller G remain in their uppermost position. If hereupon a type key be depressed, then a capital letter will come to be written. At the same time, however, the plate P is shifted, at the conclusion of the lifting motion of the type-key, into the position shown in dash-and-dot lines in Fig. 1. In so doing, the plate P strikes against the roller n^6 and turns the bar N counter to the action of the spring M, so that the projection n^3 will be thrust from the cross piece a^5 and the several parts will thereupon return into their initial position by the aid of the springs M, E and J. On the next type-key being now depressed, a small letter will consequently come to be written.

In the course of the operations just described, the device forming the subject matter of my invention does not as yet enter into action. This will, however, be the case as soon as the paper-roller G has been accidentally shifted into the uppermost position by the depression of the key d^1 , and when a type-key is not to be depressed for making a print. In this contingency, the paper-roller G is returned into its normal position by depressing one of the keys h^5 . For when

depressing one of these keys, the arm K is shifted, relatively to the lifting lever F, into the position indicated in dash-and-dot lines in Fig. 1 and the projection n^2 is at the same time forced by the cross piece k^2 of the arm K out of the path of the cross piece k^2 , so that the projection n^3 is thrust from the cross piece a^5 . This latter action takes place only for an instant; still it generally suffices for enabling the lifting lever F and consequently the paper-roller G to be lowered. The key h^5 is at once released after it has been depressed, whereupon the several parts return into their initial position provided the bar N has been properly released. In this contingency, the spring J turns the lever H in the direction of the arrow x relatively to the case shift lever D. While the levers D and H are thus turned relatively to each other, the cross piece k^2 once again forces the projection n^2 aside so that, in the event of the bar N not having as yet been released, such release will now be effected.

In case several capital letters are to be typed off in succession, then the key h^5 is first depressed and the lever h^4 thereupon turned counter to the action of the spring h^7 for such an extent until the projection h^{10} will come to engage the stationary stop plate a^4 and thus prevent the key h^5 from returning. As the key h^5 is depressed, the arm K first of all shifts into the position shown in dash-and-dot lines; the bar N at the same time executing a rocking motion owing to the action of the cross piece k^2 upon the projection n^2 . As soon as the arm K has attained the position shown in dash-and-dot lines, the pin h^2 abuts against the case shift lever D and takes it along. As a result, however, the paper-roller G is raised and retained in this upraised position, for the reason that the projection h^{10} prevents the lever H and therewith likewise the case shift lever D, from returning. If now a type-key be depressed, then the resulting displacement of the plate P will not effect a lowering of the paper-roller, but this roller will rather only return into its normal position, after the lever h^4 has been rotated counter-clockwise and, in so doing, cause the projection h^{10} to be thrust from the stop plate a^4 . For as soon as this has been done, the spring J turns the lever H in the direction indicated by the arrow x relatively to the case shift lever D, and the bar N is released in the manner previously set forth.

In the described form of execution it is, however, not absolutely impossible that, upon the paper-roller G having been accidentally shifted into its upper position, the bar N will fail to be released by depressing the key h^5 . In the modified form of execution to be presently explained, such a failure to act on the part of the releasing mechanism is rendered impossible. This modi-

- fied construction, which is illustrated in Figs. 4 to 6, is substantially the same, with the exception of the releasing device, as the form disclosed in Figs. 1 to 3, so that reference may also be made to these last-mentioned figures. In this modification the lever h^4 carrying the projection h^{10} is adapted to engage a stop ledge a^6 formed on the edge of the frame A of the machine.
10. The lever H comprises two parts, interconnected by link bolts h^{11} , of which the one part, H^{12} located toward the rear end of the machine is articulated to the case shift lever D by means of two bolts Q, and, at its 15 cranked portion h^{13} , by means of a bolt R coaxial to the bolts Q. The cranked portion h^{13} is bent up obliquely at its extremity and forms a cross piece h^{14} . Acting under the impulse of a spring M, the projection n^1 of 20 the bar N bears up against this cross piece. The part H^{12} of the lever is acted upon by a helical spring T, one end of which engages the underside of a pin h^{15} mounted on the part h^{13} of the lever, whereas its other end 25 engages the underside of the case shift lever D. The helical spring T is weaker than the spring E. Acting under the impulse of the helical spring T, the lever H bears up from below against two stops d^2 fixed to the reversing lever D. This latter is, in addition, provided with two supplementary stop pins d^3 ; these latter being disposed for a certain extent below the lever H. The lifting lever F is supported by the bolt R.
30. If it be desired to type by means of the machine illustrated in Figs. 4 to 6, first a single capital letter and thereupon a small letter, then, even as in the case first explained, one of the keys d^1 is first depressed. In so doing the lever H comes to be taken along by the intervention of the stop d^2 , so that the parts connected with the levers D and H will not come to alter their position relatively to each other. As a result 40 45 the paper-roller G is raised and retained by the bar N in this upraised position. Upon a type-key being hereupon depressed, a capital letter is caused to be written, after which the bar N is automatically released; so that, consequently, the several parts return into their initial position directly the said capital letter has been typed.
- In the event, however, of the paper-roller G having been accidentally raised, then one 50 55 of the keys h^5 is depressed. In so doing, the part H^{12} of the lever turns about the bolts Q and R, the position of which has not been affected and the cross piece h^{14} therefore moves in the direction denoted by the arrow y (Fig. 4) and effects the release of the bar N. As a result, after the key h^5 has been 60 released, the paper-roller G comes to be lowered and the several parts, impelled by their own weight and by the action of the springs 65 M, T and E, return into their normal position. During this return movement, the spring E causes the lever D primarily to bear up by means of the stop d^3 against the lever H; the bar N thus being retained in its inoperative position. Only after the lever D has returned into its normal position, the lever H comes to disengage the stop d^3 by intervention of the helical spring T and thus allows the bar N to assume its operative position. However, in this very instant 70 75 the paper-roller G has already descended so that the release action is now carried out with absolute reliability of success.
- If several capital letters are to be typed in succession, then one of the keys h^5 80 is first depressed and the lever h^4 rotated counter to the action of the spring h^7 , so that after the key h^5 has been released, a return motion of the lever H will be prevented by the projection h^{10} and the ledge a^6 . As 85 the key h^5 is being depressed, the position of the case shift lever D does not undergo any change for the present, and the part H^{12} of the lever H may therefore be rotated 90 relatively to the lever D in the direction denoted by the arrow y and the bar N thereby be shifted into an inoperative position. After that, and as the key h^5 continues to descend, the case shift lever D comes to be taken along by the intervention of the stop 95 d^3 , while the paper-roller G is raised by the aid of the lifting lever F. The paper-roller will only be enabled to descend again on the lever h^4 being turned counter-clockwise and when the projection h^{10} has been 100 thrust from the ledge a^6 .
- Claims:
1. In a typewriting machine the combination with a movable platen and a case shift mechanism of a locking member for retaining the platen in its raised position and a case shift release mechanism functioning when moved relatively to said case shift mechanism, said locking member projecting into the path of said case shift release and displaceable thereby independently of the typewriter key levers and means for coupling said case shift and release mechanisms so as to permit them to be moved together or said release mechanism moved 110 relatively to said case shift mechanism.
2. In a typewriter, a movable platen, a case shift mechanism, a locking member for retaining said platen in its upper position, a case shift release mechanism and means 120 carried by said release mechanism and engaging said case shift and said locking member whereby said case shift and release mechanisms may be operated simultaneously or said release mechanism moved relatively 125 to said case shift mechanism and caused to displace said locking member and thereafter to engage said case shift mechanism.
3. In a typewriting machine a platen, a case shift lever, a locking mechanism for 130

retaining said platen in its shifted position, a key operated releasing lever, a releasing member connected to and operated by said releasing lever and adapted to engage said locking member to move the same to inoperative position upon a relative movement between said releasing and case shift levers, and projections formed on said releasing lever in the path of said case shift lever, whereby movement of said releasing lever will first displace said locking member and thereafter cause a movement of said case shift lever.

4. In a type writing machine a platen, a case shift lever, a locking member for retaining the platen in its shifted position, a key operated releasing lever, a releasing member connected to and operated by said releasing lever, said locking member being provided with a projection extending into the path of said releasing member, the releasing member being displaceable at right angles thereto whereby said releasing member will transiently shift said locking member into an inoperative position upon a relative movement between said case shift and releasing levers and means for coupling said case shift and releasing levers whereby they

may be actuated simultaneously or said releasing lever moved relatively to said case shift lever.

5. In a typewriter a shiftable platen, a case shift mechanism, a locking member for locking said platen in its raised position, a case shift release mechanism functioning when moved relatively to said case shift mechanism, said case shift and release mechanisms being disposed adjacent one another, and projections carried by said release mechanism and engaging said case shift mechanism whereby said mechanisms may be operated simultaneously or said release mechanism moved relatively to said case shift mechanisms, the movement of said release mechanism relative to said case shift mechanism causing a displacement of said locking member to permit said platen to return to its lower position.

The foregoing specification signed at Essen, Germany, this 22nd day of November, 1920.

KARL AUGUST LEHMANN.
